UNITED STATES PATENT OFFICE.

BRAINARD CLARK, OF ROZELLE, NEW SOUTH WALES, AUSTRALIA.

METAL CAP FOR HERMETICALLY SEALING BOTTLES.

Application filed May 23, 1923; Serial No. 640,975, and in Australia February 5, 1923.

This invention relates to the metal seals that are used for hermetically sealing bottles and has particular reference to an invention described and illustrated in the 5 specification and drawings accompanying application No. 640,479, for Letters Patent of the United States of America, filed May 21st, 1923.

The prior invention referred to was devised for the purpose of providing a metal seal of the type referred to above and for ensuring that a means for removing them would always be ready at hand.

It consists of a metal cap having a shallow crimped side wall part of which is extended to form a specially shaped tag in which is a slot adapted to receive the tail piece of another cap which is used as a lever to force the cap off the bottle. If another cap is not available a plain thin strip of metal may be passed partly through the slot and used as a lever instead of the extended portion of another cap.

It has been found however, that in some 25 cases the opening means are wrongly used in that after the tag upon one seal is passed through the slot in another tag the two bottles are simply pulled away from one another with the result that the tags pull apart 30 without effecting the purpose for which they were designed.

The present invention has been designed to remove this disability and consists in providing a means whereby the extremity of one tag may be first inserted in the slot of another tag and having been turned so that the ends lie flat against each other any attempt to pull them apart will cause them to lock together. One method of effecting this 40 object is by providing each tag with a slot having downwardly and inwardly tapered sides the extremity of each tag being D-shaped the lowermost edge of the tag forming the curve of the D. The relative sizes 45 of the slot and the D-shaped end will in all cases be such that the latter may be passed through the slot in another tag by first entering one end of the D and then giving it a circular movement in a plane substantially at right angles to the other tag.

In order that the invention will be properly understood it will now be particularly described and reference will be made to the accompanying sheet of drawings in 55 which:

Fig. 1 is a plan of a piece of sheet metal blanked out ready to be stamped.

Fig. 2 is an elevation of the stamped cap showing the tag and slot therein.

Fig. 3 is a perspective view of the cap 60 fixed upon the top of a bottle.

Fig. 4 is a similar view to Fig. 3 but the tag has been bent upwardly and a flat metal lever inserted in the slot in readiness to lever the cap off the top of the bottle. 65

Fig. 5 is a perspective view of the top portion of two bottles to which the caps have been fixed and showing the method adopted when one cap is used to remove another. 70

Fig. 6 is a perspective view of two caps showing the D shaped end of a tag on one cap being inserted into the slot in the tag of another cap. 75

Near its lower extremity the tag on the 75 cap 8 is provided with a recessed opening 9, extending inwardly towards its centre from each side, the lowermost edge 10 of the tag 7 being curved so as to form the end 11 into a D shape. The slot 12 is situated at a suitable point above the recessed openings 9 and will be provided with two oppositely positioned downwardly and inwardly tapered edges 13 which when in use will engage the projecting ends of the D-shaped end 11 of the tag 7 on another cap as shown at Fig. 6. 80

To remove the cap from a bottle either a spare cap or a cap secured upon another bottle and constructed according to this invention may be used. If the latter course is adopted each tag will be bent outwardly from their respective bottles sufficiently to enable the D-shaped end 11 of one cap to be inserted in the slot 12 in the other cap in a 95 plane at substantially right angles thereto. In that position the bottle upon which is the tag that is being inserted is then moved so as to bring the ends of the tags flat against each other as shown at Fig. 5 when it will be given a further hinge-wise movement upon the tags until the caps themselves abut against each other so that one of them may be levered off its bottle and as the resultant separating strain is brought 100 to bear upon the tags the extremities of the D-shaped end 11 will slide over the tapered edges 13 by which they will be engaged on the opposite side to that from which they 105 were entered. 110

The improvements described and claimed in this specification do not prevent the use of a metal lever 14 as shown at Fig. 4.

I claim:—

- 5 1. A bottle cap comprising a body provided with a skirt portion adapted to embrace the mouth of a bottle, a tag carried by the body having a slot therein, means permitting the lateral introduction of the tag of a discarded cap into said slot and also permitting the tag of said discarded cap to be subsequently moved in substantial alinement with the first mentioned tag whereby the tag of the discarded cap may be utilized as 10 a lever for effecting the removal of the first mentioned cap and a shoulder on the tag preventing the longitudinal withdrawal of the tag of the discarded cap through the slot of the first mentioned tag after the tags have 15 been moved into alignment with one another.
2. A bottle cap comprising a body provided with a skirt portion adapted to embrace the mouth of a bottle, and a tag carried by said body provided with a slot and a recess lying outwardly of said slot, said recess defining a retaining shoulder facing said slot, said recess permitting the lateral 20 25

introduction of the tag into the slot of the tag of another cap and also permitting said tags to be moved into alinement with one another subsequent to the insertion of the tag laterally into the slot, said shoulder acting to prevent the longitudinal withdrawal of the tag through said slot. 30 35

3. A bottle cap comprising a body provided with a depending skirt portion adapted to embrace the mouth of a bottle, a tag carried by said body and provided with a slot adapted to receive the end of the tag of a second cap, and shoulders carried by the tag adapted to coact with the walls of the slot to prevent the longitudinal withdrawal of the tag of one cap through the slot in another cap. 40 45

4. A bottle cap as claimed in claim 3 characterized in that the tag is provided with a recess lying contiguous to the shoulder permitting the lateral introduction of the tag of one cap into the slot of another cap and also permitting the tags to be subsequently moved into alinement with one another. 50

In testimony whereof I have signed my name to this specification.

BRAINARD CLARK.
